UNITED STATES PATENT OFFICE.

DANIEL HOGAN, OF HOBOKEN, NEW JERSEY, ASSIGNOR TO MEINECKE & COMPANY, OF NEW YORK, N. Y., A CORPORATION OF NEW JERSEY.

SURGICAL-ACCESSORY-SUPPORTING APPLIANCE.

1,199,553.

Specification of Letters Patent. Patented Sept. 26, 1916.

Application filed June 3, 1915. Serial No. 31,852.

To all whom it may concern:

Be it known that I, DANIEL HOGAN, a citizen of the United States, residing at Hoboken, in the county of Hudson and State 5 of New Jersey, have invented new and useful Improvements in Surgical-Accessory-Supporting Appliances, of which the following is a specification.

My present invention relates generally to 10 surgery and more particularly to an appliance for supporting surgical accessories in a proper and convenient position for use by or in the treatment of a patient confined to his or her bed.

15 The object of the invention is to provide a simple and easily manipulable surgical accessory-supporting appliance that may be readily and quickly attached to any convenient frame-part of an ordinary bed 20 whether the frame-part extends vertically or horizontally, whereby the accessory, whatever may be its intended purpose, will be properly positioned with relation to the patient to secure the best results with as little inconvenience to the patient as possible.

25 One of the principal purposes of the invention is to provide a simple and thoroughly practical appliance especially adapted for supporting an irrigator or fountain syringe, 30 said appliance being readily attachable to any part of the frame of an ordinary bed or to an operating or bed-side table where the irrigating operations may be carried on to the best advantage and with the least possible 35 annoyance and discomfort to the patient.

Briefly and specifically stated the invention comprises a clamping member having a pair of pivotally connected clamping jaws adapted to be brought into clamping engagement with a vertical or a horizontal frame-part of a bed or bed-side table, the 40 said jaws being constructed and arranged to embrace bed-frame parts or parts of a bed-side table having different cross-sectional 45 diameters. In other words the clamping member is adjustable and therefore applicable to frame-parts of different shapes and diameters. One of the said clamping jaws is preferably provided with plural means 50 arranged at right angles to each other, either one of which means is adapted to removably and interchangeably receive and retain, in

vertical position, any one of a number of accessory-supporting members, whether the said clamping member is attached to a vertical or to a horizontal frame-part of the bed, there being a locking device associated with and common to each of the said plural receiving and retaining means for maintaining the selected accessory-supporting 60 member in any desired position of vertical adjustment.

The invention further comprises the features of construction and combination and arrangement of parts hereinafter more fully 65 described and particularly pointed out in the appended claims.

In the accompanying drawings wherein I have illustrated a preferred embodiment 70 of the invention, Figure 1, is a perspective view of an ordinary metal bed such as usually employed in hospitals and to which I have shown my invention applied at both the head and the foot of the bed. Fig. 2, is an end elevation of one form of clamping 75 member constructed according to the invention, said member being shown in clamping engagement with a frame-part of a bed. Fig. 3, is a vertical section on the line 3—3 of Fig. 2. Fig. 4, is a detail perspective view of the 80 locking device looking toward the inner face thereof. Fig. 5, is a perspective view of the complete appliance in one form, the particular accessory-supporting member illustrated in the figure being especially adapt- 85 ed to support an irrigating vessel such as a tank or water bag. Fig. 6, is a detail sec- 90 tional view showing the swivel connection between the accessory-supporting rod and its hooked end. Fig. 7, is a perspective view 95 of the clamping member, looking toward the plural supporting and retaining means, the locking device being removed. Fig. 8, is a perspective view of a portion of a bed showing the accessory-supporting appliance 95 clamped to a horizontal rail-part thereof. Fig. 9, is a similar view showing the appliance clamped to a horizontal top-rail of a bed, the particular appliance in the instance shown being adapted for use in the 100 treatment of fractured thighs.

Inasmuch as my accessory-supporting appliance is especially adapted for use as an attachment to beds, I have shown, in Fig. 1

of the accompanying drawings, an ordinary iron bedstead such as usually employed in hospitals and as frequently found in homes, and wherein such bedsteads have vertical 5 posts 1 at both the head and the foot end of the bed, and horizontal side rails 2 connecting the said vertical posts, the latter posts at both the head and the foot end of the bed being usually joined or connected by means 10 of a horizontally arranged connecting end rail 3. Of course the particular construction of bed forms no part of the present invention and it is to be understood that the appliance may be attached to any ordinary 15 bed or bed-side or operating table and to any desired and accessible part of the frame thereof.

The improved clamping member in the embodiment of the invention illustrated, 20 and as more clearly shown in Figs. 2, 3, 5 and 7, consists primarily of a pair of oppositely arranged jaws numbered 4 and 5 respectively, said jaws being pivotally connected by means of a pintle 6 passing through alined sleeve portions 7 of the jaws. The jaws are preferably oppositely arched or curved and the inner face of each curved portion is preferably covered or faced with a strip of yielding material 8, such as fabric 25 or rubber, to prevent the jaws from scratching or marring the frame-part of the bed or other support to which the clamping member is attached. One of the jaws, as for instance the jaw 4, has a threaded screw 9 pivotally connected at 10 to the outer end 30 thereof, the said screw 9 being preferably arched as shown and having a thumb-nut 12 threaded thereupon. The other jaw, as 35 5, has a substantially flat wall 13 at its free end, there being an open slot or notch 14, Fig. 5, cut into said flattened wall to receive the threaded screw 9 when the jaws are brought into clamping engagement with the frame-part of a bed, the clamping action 40 of the jaws upon such frame-part being brought about by screwing the thumb-nut 12 upon the threaded screw 9 until the end of the nut is in facial contact with the flat wall 13 of the jaw 5.

50 One of the jaws of the clamping member is provided with plural rod-supporting and retaining means arranged at right angles to each other, with one or the other of which an accessory-supporting rod may be associated in order to hold the said rod in a vertical position whether the said clamping device is attached to a vertical or to a horizontal frame-part of the bed. The plural supporting and retaining means, in the instance shown, consists of a pair of open ended sleeves number 15 and 16 respectively, said sleeves being arranged at right angles to each other and preferably arranged adjacent the pivotal point 6 of the jaws, the 55 sleeve 15 extending parallel with the said

pivotal point 6, and the sleeve 16 arranged at right angles to the sleeve 15, the openings through the sleeves intersecting each other at a central point. The openings in the sleeves are of substantially the same diameter, so as to removably and interchangeably receive accessory-supporting rods of different types as will be more clearly described hereafter. 70

In order to securely lock the accessory-supporting rod, when said rod is brought into associated relation with one or the other of the sleeves, I have provided a locking device which, in the instance shown, is common to both the said plural means or sleeves, the said locking device being adapted to be moved into and out of locking engagement with the rod and adapted to support the rod in any desired vertically adjusted position. 80

In the instance shown, the locking device consists of a non-rotatable plate 17 having locking lugs 18 projecting from the inner face thereof, said locking lugs each extending through an opening 19 formed 90 through the outer wall of each sleeve. In the particular construction of locking device illustrated, there are two pairs of lugs, one pair being arranged in a plane at right angles to the other pair so that in the said 95 construction there are two locking lugs associated with each sleeve whereby the accessory-supporting rod will be gripped simultaneously by both lugs when said rod is associated with either one or the other of the sleeves. The locking device, or plate 17, is supported by a threaded screw 21 projecting outward from the outer face of one of the sleeves, the said plate 17 being provided with an opening through which the screw 105 may pass. A wing-nut 22 is threaded upon the screw 21 and is adapted when rotated to engage the outer face of the plate and force the locking lugs into engagement with the accessory-supporting rod inserted in 110 one of the sleeves. The outer end of the screw 21 is preferably flanged or swaged sufficiently to prevent the wing-nut from being removed therefrom, thus obviating any danger of the parts becoming separated 115 and lost.

I prefer to so arrange the locking plate 17, with relation to the wing-nut 22, that the said plate will be positively moved in and out, or into and out of rod-locking position 120 upon simple turning movement of the wing-nut, and to this end I provide the wing-nut with a flange or flanges 23 which is or are swaged over the inner face of the locking plate 17, around the opening therethrough as more clearly shown in Fig. 3 whereby the plate and the nut will be inseparably but swivelly joined, so that the nut may be rotated without effecting rotation of the plate. It will be noted that in the construction 130

illustrated, the locking plate 17 is mounted so that it may be moved into and out of locking engagement with the accessory-supporting rod by simple turning movement of the wing-nut, the said plate itself not being rotated during rotation of the nut, but having an in and out movement only. By reason of this construction of non-rotatable locking plate, I am able to obtain a better gripping action upon the accessory-supporting rod. While I have shown the locking plate as provided with two pairs of locking lugs, I do not wish to be understood as limiting myself to this specific construction as obviously a plate with a lesser number of locking lugs arranged to coöperate with the two sleeves could be employed without departing from the spirit of the invention.

The accessory-supporting device, in one of the instances shown, consists of a tubular rod 25, which if desired, may be made in one or more sections and suitably joined as by a threaded detachable connection 26, Fig. 5. By making the rod in detachable sections the appliance as a whole may be more closely compacted for carrying or packing purposes. The rod is of such cross-sectional shape and diameter as to freely but closely fit within one or the other of the receiving and retaining sleeves 15 and 16, depending upon whether the clamping device is attached to a vertical or to a horizontal rail or frame-part of a bed or other support. The upper end of the rod 25 is provided with a head 27 having a swiveled connection with the rod so that it may be rotated thereupon in a horizontal direction, the said head being provided with one or more hooks 28, 29, one of which is preferably arranged closely adjacent the rod 25 so that when an accessory in the form of an irrigating tank or vessel such as 30, Fig. 1, is suspended from the hook 28, the flat wall 31 of said vessel will lie close to and be supported in part by the rod 25. The hook 29 may or may not form a part of the head, but when it is employed its function is to support a vessel or tank not provided with a flat wall such as the wall 31 before referred to. If desired I may provide the head 27 with a ring 27a, Fig. 6, by which the rod may be suspended from a suitable supporting pin or hook when not in use.

The head 27 may be swivelly connected to the end of the rod 25 in any suitable manner and in Fig. 6, I have illustrated one form of such a connection which consists in providing the head with a stud 32 which passes through an aperture in a disk 33 fitted in the upper end of the tubular rod 25, the inner end of the stud being split or coned and swaged over laterally to effect the swivel connection. The object of swivelly connecting the head is to enable the surgical accessory supported thereby, such as an irrigat-

ing vessel, to be brought into convenient position for use after the rod 25, has been adjusted and locked.

Instead of providing the accessory-supporting rod with a hook or hooks as described, I may provide the rod with a grooved wheel or pulley 34, as more clearly shown in Fig. 9, and over which a weighted cord 35 may pass, this form of device being useful in the treatment of fractured thighs and the like wherein it is desirable to exert a constant pull upon the limb of a patient as by means of a cord having a weight as 36 attached to the free end thereof. In Fig. 9, wherein this form of accessory-supporting rod is shown, the clamping member is shown attached to the horizontal top rail 3 at the foot end of the bed with the pulley 34 arranged below said rail. Obviously the rod could be reversibly arranged in order to bring the pulley 34 to a position above the rail of the bed.

In Fig. 1, I have shown, at the head of the bed, one of my improved clamping members as holding or supporting an arm carrying in its outer end a holder for a sanitary sputum cup (not shown) such as are now commonly used in hospitals and sanatoriums, the said holder, in the instance shown, consisting of a skeleton frame made up of a pair of substantially U-shaped metal strips 38 joined by a U-shaped connecting strip 39, the upwardly extending legs 40 of which are joined to the strips 38, the sanitary sputum cup (not shown) being supported by the holder formed by said strips.

It will be understood from the foregoing detailed description of the invention that the clamping member may be easily and quickly brought into clamping engagement with either a vertical or a horizontal frame-part of a bed and that whatever may be its position of attachment, one or the other of the plural rod-receiving and retaining means or sleeves will be in position to support the accessory holding rod in a vertical position. It will also be understood that the said rod may be adjusted vertically to bring the swiveled head thereof with its associated hook to different heights relative to the patient occupying the bed. This has especial advantages as in cases where the appliance is used to support an accessory such as an irrigator wherein a strong or a mild flow of the irrigating fluid is desired depending upon the particular treatment to be given the patient.

It will be understood that the clamping member together with the accessory-supporting rod constitute in effect a unitary structure, the one being combined and co-operating with the other to produce the complete appliance; although I wish it understood that other forms of supporting rods, than those herein shown, may be used.

in connection with my improved clamping device, and also that my improved supporting rods may be employed with other forms of clamping devices, without departing from the spirit of the invention.

What I claim is:

1. An appliance of the character described, comprising a clamp consisting of a pair of pivotally connected clamping members having arched faces adapted to embrace vertical or horizontal posts or rails of different diameters, means for retaining said pivoted members in clamping relation, plural means arranged at right angles to each other, carried by one of said pivoted members adjacent the pivotal point thereof for receiving and retaining in vertical position an accessory holding rod, depending upon whether the clamp is applied to a vertical or to a horizontally positioned post or rail, an accessory holding rod interchangeably applicable to either of said plural receiving and retaining means, and a locking device having separate locking lugs common to both said plural means for locking the said accessory holding rod in different vertically adjusted positions according to whether the said holding rod is arranged in co-operative relation with one or the other of the said plural means.
2. An appliance of the character described, comprising a clamp having a pair of pivotally connected jaws, means for retaining said jaws in clamping engagement with a suitable support, a pair of open ended sleeves arranged at right angles to each other carried by one of said jaws adjacent its pivotal point, said sleeves

adapted to receive and retain an accessory holding device in vertical position, a non-rotatable locking device common to both said sleeves, said locking device having gripping portions passing through the walls of each of the sleeves and intersecting the openings therethrough, and means for causing the said gripping portions of the locking device to enter the sleeves.

3. An appliance of the character described, comprising a clamp having a pair of pivotally connected jaws, means for retaining said jaws in clamping engagement with a suitable support, a pair of open ended sleeves arranged at right angles to each other, carried by one of said jaws, said sleeves adapted to receive and retain an accessory holding-device in vertical position, a locking device common to both said sleeves, said locking device having gripping portions adapted to pass through the walls of each of the sleeves so as to intersect the openings therethrough, a threaded stem extending outward from a point centrally of the pair of sleeves, said stem extending through an opening in the locking device, a nut threaded upon the stem, and a swivel connection between the nut and locking device for positively moving the gripping portions of said device into and out of gripping position.

In testimony whereof I have hereunto set my hand in presence of two subscribing witnesses.

DANIEL HOGAN.
